SHEET METAL HEATING STOVE

Jerome M. Higman, Rosemead, Calif.; Anna H. Higman administratrix of said Jerome M. Higman, deceased

Application December 26, 1945, Serial No. 637,155

1 Claim. (Cl. 126—59)

1

This invention relates to heating stoves and has for an object a provision of a heater which is particularly adapted for use as a camp heating stove, but which is not necessarily limited to such use as it is also capable of affording convenience and comfort, both indoors and out, in many different types of use.

A more detailed object of the invention is to provide a heater which is readily portable, this object being attained by so designing the heater that it is small in size, light in weight, and employs a type of fuel which obviates the necessity of connecting the heater to a flue or vent.

A further object of my invention is to provide a heater of the general class indicated, which can be manufactured at very low cost, and yet which is highly efficient in that it is economical of fuel and is capable of providing heat in much larger volume than ordinarily expected of heaters of smaller size or within its general price range.

Another object is to provide, in a heater of the class described, details of construction which operate to prevent heat from passing from the heater to the surface upon which it is supported, in such quantity as to endanger the latter.

A still further object of my invention is to provide a heater which is of such small size and light weight that it is capable of being used in locations to which heaters of more conventional design are unadaptable, such as under a camp table or under a camp stool, so that the heater serves adequately in supplying warmth to one or more persons in its immediate vicinity even when being used out of doors.

It is another object of the present invention to provide an improved heater which is constructed entirely of sheet metal and portions of which are fastened together by interlocking parts of the sheet metal itself instead of requiring the manipulation of such fastening devices as rivets, screws, or the like, thus reducing the time and labor required for its assembly.

The invention possesses other objects and valuable features, some of which, with those enumerated, will be set forth in the following description of the embodiment of my invention illustrated in the drawing accompanying and forming part of the specification. It is to be understood that I do not limit myself to the showing made by the said drawing and description, as I may adopt variations of the preferred embodiment of my invention without departing from the scope thereof as defined by the claim.

Referring to drawings:

Figure 1 is a perspective view of a heating stove

2

constructed in accordance with the principles of the present invention.

Figure 2 is an enlarged view in vertical medial section.

Figure 3 is a compound view in horizontal section, the planes of section being indicated by the lines 3—3 of Figure 2.

Figure 4 is a perspective view of an accessory designed for use within the heating stove of Figure 1.

Figure 5 is a view similar to Figure 2, but showing the accessory of Figure 4 in operative relation within the stove.

The present invention contemplates provision of a heating stove of such small size and light weight that it is particularly adapted for use as a camp heating stove, not only because of its ready portability but also because it is capable of affording much convenience and comfort when positioned under a table about which several persons are seated. When so used, a stove incorporating the principles of the present invention has been found to provide ample heat to keep several persons adequately warm even when used out of doors during relatively cold weather.

Another manner of use which has been found to afford much comfort and convenience is to place a lighted heating stove incorporating the principles of the present invention under the camp stool or chair on which a person is seated. However, it should be understood that the stove of the present invention is also adapted for use indoors, one of the features of the stove which makes such use feasible being certain of its details of construction which protect the surface, such as a wooden or even a carpeted floor, from the heat emanating from the stove with ample security to avoid all danger to such floors even while the stove is operating at full capacity. Owing to the fact that the stove is designed to use fuel in the form of glowing coals, such for example as charcoal or "briquettes" which, after having been initially lighted, cease to give off smoke or fumes in objectionable quantity, it is unnecessary to connect the stove of the present invention to any flue or vent outlet.

Specifically describing the details of construction of my improved and simplified heater and referring specifically to the drawing, the body 6 of the heater comprises an upright shell 7 preferably of cylindrical form formed by rolling a flat sheet of sheet metal so as to bring its end edges 8 and 9 into overlapping relation and fastening them together as by a plurality of rivets at 50 suitably spaced intervals along the edges 8 and 9.

Greater convenience is afforded, however, by employing fastening means of a non-permanent nature, such as removable screws 11 either threaded directly into the sheet metal or into nuts 12 on the opposite side of the overlapping edges 8 and 9 from that on which the heads of the screws are disposed, or even by merely threading a piece of wire through several holes at suitably spaced intervals throughout the length of the edges 8 and 9. By using non-permanent fastenings, the body 6 is subject to being straightened out to assume a substantially flat position, with the result that thus the disassembled stove can be packed in a smaller space and thus be carried more conveniently as a piece of camping equipment.

A pair of vertically spaced, horizontal plates 16 and 17 are fitted within the shell 7, the upper plate 16 serving as a grate to support the fuel 18, whereas the function of the lower plate 17 is that of shielding the surface upon which the heater is supported from heat radiated downwards from the grate 16 and also to prevent any ashes or coals which may fall through the perforations 19 which are provided in the grate 16, from falling onto the stove's supporting surface. The lower plate 17 is spaced a substantial distance above the bottom edge 21 of the shell 7 so that even though the lower plate 17 may become quite warm, the supporting surface will be adequately protected against being scorched.

The upper plate or grate 16 is supported within the shell 7 by means of a plurality of tongues 22 in horizontal alignment with each other and extending inwards with respect to the shell 7. Each of these tongues 22 is formed by severing a preferably triangular piece from the sheet metal of which the shell 7 is formed, each tongue being severed throughout all but one edge and then by bending the tongue inwards along that unsevered edge, thus leaving an aperture 23 in the shell 7 corresponding in shape to the tongue. Consequently the apertures 23 left in the shell 7 when the grate-supporting tongues 22 are formed, serve to establish communication between the exterior of the heater and the space 24 within the heater between the two plates 16 and 17.

A similar series of tongues 26 below the lower plate 17 support this plate 17; and the apertures 27 left in the shell 7 when the tongues 26 are bent inwards establish communication between the exterior of the heater and the space 28 within the heater below the lower plate 17. This provides adequate circulation of air below the lower plate 17 so as further to guard against scorching the stove's supporting surface.

The tongues 22 and 26 are all formed by bending them inwards and upwards so that they extend inwards from the uppermost edges of the apertures 23 and 27 respectively. Another series of tongues 31 are bent inwards and downwards so that they extend inwards from the lower edges of the apertures 32 left in the shell 7 when the tongues are bent inwards. These tongues 31 engage the upper surface of the upper plate 16 with the result that this grate-forming plate 16 is gripped firmly between the tongues 31 engaging its upper surface and the tongues 22 engaging its under surface.

Still another series of similarly formed tongues 36 extending inwards from the lower edges of apertures 36 in the shell 7, engage the upper surface of the lower plate 17 in overlapping relationship therewith, so that this plate 17 is gripped between the tongues 34 engaging its upper surface and the tongues 26 engaging its under surface.

Thus it may be seen that the apertures 36, as well as the apertures 23, open into the space 24 between the two plates 16 and 17 so as to assure very thorough circulation of air within this space and provide additional protection against overheating of the lower plate 17.

The apertures 32 as well as the perforations 19 in the grate 16 permit entry of air to the space 41 above the grate 16 within which the fuel 18 is disposed, with the result that ample provision is made for circulation of air through the fuel 18 to assure thorough and amply rapid combustion of the fuel.

Since the two plates 16 and 17 are merely gripped between the upper and lower tongues associated therewith and preferably are not permanently attached thereto, this feature co-operates with the removable nature of the fastening means 11 and 12 whereby the end edges 8 and 9 of the shell 7 are screwed together, in permitting disassembly of the stove as described hereinabove.

A top plate 46 preferably provided with a large number of relatively large apertures 47, rests upon the upper edge 48 of the shell 7, this plate 46 being retained against accidental displacement by a series of downwardly extending flanges 49 struck from the material of the plate 46 at suitably spaced intervals throughout its peripheral edge 30 and at such distance inwards from the outer edge of the plate that they engage preferably the inner surface of the shell 7, as clearly shown in Figure 2.

I also provide a handle 51 in the form of an inverted U-shaped bail, the lower ends 52 of which are bent inwards so as to pass through suitably positioned holes 53 in the shell 7 adjacent its upper edge, these inwardly extending portions 52 preferably being bent upwards as indicated at 54 within the shell 7 so as to retain the bail 51 in position under normal circumstances of use but to permit easy removal of the handle when it is desired to disassemble the heater.

Thus it may be seen that I have provided a heater of very inexpensive construction and very light in weight which is subject to being taken down so that all of its parts are substantially flat, with the result that it is very easily portable as a piece of camping equipment. However, owing to the manner in which the plates 16 and 17 are supported and retained within the assembled stove, i. e., without the necessity of manipulating any screws, rivets, or other fastening devices, assembly of the stove from its dismounted to its operating arrangement can be performed with the utmost ease. After the stove has been assembled, a supply fuel 18 such as charcoal or briquettes, is placed within the fuel space 41 and this fuel is most easily lighted by stuffing a few pieces of paper or rags saturated with alcohol or kerosene 60 through the apertures 23 and then igniting them so that flames therefrom will pass upwards through the perforations 19 and ignite the fuel 18.

I found that the presence of the apertures 32 in the shell 7 just above and around the edge of the grate 16 affords extra convenience in permitting the removal of any excess amount of ashes within the fuel space 41. After the stove has been in operation for any length of time its fuel 18 can be caused to burn more rapidly and thus the heat output of the stove increased merely by picking the stove up with its bail 51 and then rotating it so as to turn the stove about its vertical axis through say a quarter turn. This will cause the ejection of ashes from the apertures 32 by centrifugal action and thus increase the rate at which

the fuel 18 is burning. On the other hand, if the heater is left undisturbed after being charged with fuel and having that charge of fuel ignited, it can be relied upon as a source of heat in a volume adequate for many purposes and for a greatly prolonged period of time. It has been found in actual use that when operated in this manner the heater of the present invention is capable of keeping the interior of a small tent comfortably warm for more than five hours even when the outside temperature falls to below freezing.

Figures 4 and 5 illustrate an accessory which has been found to afford convenience when a maximum rate of heat output is desired. This accessory comprises a supplementary grate member 61 in the form of a frustum of a cone, the base of which is slightly less in diameter than the inside of the heater, while its height is less than the distance between the upper plate 16 of the heater and the heater's upper edge. Consequently the supplementary grate member 61 is receivable within the upper portion of the body 6 of the heater, supported above and closely adjacent the upper plate member 16 as by resting upon the upper surfaces of the tongues 31 which engage the upper surface of the upper plate 16, as clearly illustrated in Figure 5. The frusto-conical grate 61 can most easily be made from a substantially arcuate strip of sheet metal curled so as to bring its two end edges 62 and 63 into overlapping relation where they can be firmly secured together as by rivets 64 as illustrated in Figure 4. A plurality of perforations 66 is formed in the strip of sheet metal, preferably while it is still flat and, also preferably, the upper end of the supplementary grate member 61 is left open, thus providing an aperture 67 at the top of the frusto-conical grate 61 which optionally can be left open or can be closed as by a cap 68 which preferably is formed complementary to the upper end of the grate member 61 and is provided with a convenient handle 69 having a ring 71 at its upper end which facilitates installing and removing the cap 68 when the stove is in operation and when the cap 68 is hot.

When the heater is employed with the auxiliary frusto-conical grate member 61 installed therein, the supply 76 of fuel within the heater is assured a more thorough flow of air therethrough and consequently a more efficient supply of oxygen, which will thus cause a more rapid rate of combustion of the fuel. Instead of being permitted to form a solid bed of coals, as illustrated in Figure 2, the bed formed by the auxiliary grate member 61 is hollow and every portion of the bed of coals is closer to a source of fresh air than

is the case when the auxiliary grate member 61 is not used. When igniting the fuel, and when it is desired to cause the fuel to be consumed at the maximum rate and thus give off the largest possible supply of heat, the cap 68 is placed in position upon the otherwise open top 67 of the supplementary grate 61, thus causing all of the air flowing upward through the frusto-conical member 61 to pass through the fuel. However, after the fuel has been ignited and it is desired to lessen the rate of combustion and thereby prolong the time before which replenishment of fuel will be necessary, the cap 68 can be removed, thus permitting a large percentage of the air passing upward through the frusto-conical member 61 to escape through the open top 67 without actually passing through the bed of coals. The ring 71 in the upper end of the cap's handle 69 is adapted to receive the end of a metal rod, such as a poker, or a small branch, so that the cap 68 can be installed or removed easily even when hot.

I claim:

A heating stove of the character described comprising a housing of sheet metal, two series of tongues severed from said sheet metal along all but one edge of each tongue, each of said tongues being bent along said unsevered edge thereof to extend inwards of said housing, and means providing a grate supported within said housing upon the tongues of one of said series, the apertures left in said sheet metal by bending the tongues on which said grate is supported establishing communication between the exterior of said housing and the interior thereof below said grate, the tongues of the other of said series extending into overlapping relation with the upper surface of said grate, and the apertures left in said sheet metal by bending said overlapping tongues establishing communication between the exterior of said housing and the interior thereof above said grate.
